[57] **CLAIM**

The adjustable securing device, as shown and described.

DESCRIPTION

FIG. 1 is a perspective view of an adjustable securing device in accordance with an embodiment of the present invention, with the adjustable securing device in an open position for receiving a flexible line, such as a rope;

FIG. 2 is a perspective view of the adjustable securing device of FIG. 1 with the securing device in a fully closed position;

FIG. 3 is a side elevational view of the adjustable securing device of FIG. 1;

FIG. 4 is a top view of the adjustable securing device of FIG. 1; and,

FIG. 5 is a bottom view of the adjustable securing device of FIG. 1.

The broken lines that define the bounds of the upper and lower portion of the claimed design form no part thereof.
